UNITED STATES PATENT OFFICE.

CHARLES LAVALLEE, OF NEW MARKET, NEW HAMPSHIRE.

LET-BACK MECHANISM FOR LOOMS.

No. 907,378.

Specification of Letters Patent.

Patented Dec. 22, 1908.

Application filed June 27, 1908. Serial No. 440,621.

To all whom it may concern:

Be it known that I, CHARLES LAVALLEE, a subject of the King of Great Britain, residing in New Market, in the county of Rockingham and State of New Hampshire, have invented a new and useful Improvement in Let-Back Mechanisms for Looms, of which the following is a specification.

This improvement relates to that class of 10 inventions or devices in which when the take-up of the cloth is stopped by the detection of a technically thin place produced by an absence of filling, the cloth is let back in order that when the fresh filling is laid it will 15 be by the stopping of the take-up and the letting back of the cloth be resumed where the old filling failed.

The present invention relates to a certain 20 novel construction and arrangement of parts, fully described below, and illustrated in the accompanying drawings, whereby an improved mechanism for the purpose is produced which is applicable to differently constructed looms, whereby a more perfect adjustment of the device and its parts are 25 provided, and whereby the efficiency of the operation is enhanced.

In the drawings—Figure 1 is an elevation 30 of a portion of one end of a loom, showing a part of a take-up mechanism, and with my improved let-back mechanism applied and in its normal position, that is, with the loom operating normally. Fig. 2 is an enlarged view in detail showing in dotted lines my improved let-back mechanism in the position 35 assumed when the filling is absent, and showing in full lines the position of the parts when the machine is ready to start and let back the cloth. Fig. 3 is a detail of the segment-rack 40 removed. Fig. 4 is an end view of the let-back mechanism. Fig. 5 is a section taken on line 5—5, Fig. 1.

Similar letters of reference indicate corresponding parts.

45 *a* represents a portion of the frame of a loom of well known construction, and *b* is the cloth supported by a suitable take-up of which *c* is a ratchet-wheel making a part of the pick-gear and supported by the frame. 50 *d* represents the cam-shaft on which is rigidly secured an eccentric *e* from which the arm *f* extends into engagement with the take-up-wheel or ratchet-wheel *c* by means of a suitable pawl indicated by dotted lines 55 at *g*. All these parts are well known and operate in the manner common in the art, and

require no detailed explanation. I do not confine myself to their exact construction and arrangement, except so far as such construction and arrangement are necessary to 60 the operation of my invention.

Rigid on the usual rock-shaft *h* is an arm *k* whose outer end is adjustably and rigidly secured by a suitable bolt *i* to the outer end of a bar *l* by means of a slot *m* therein, small 65 ears *n* being preferably provided on the arm *k* and resting on the upper surface of the bar *l*. This bar *l* is formed at its opposite end into an integral hook *o*, and it is provided between the hook and the slotted portion with 70 a pivot *p* which extends through an elongated slot *q* (see Fig. 3) in a segment-rack *r* which is thus rendered capable of vertical movement with relation to the pivot. This 75 rack is supported by the pivot *p* between the bar *l* and a back-plate *s*, also supported by said pivot. The lower edge of the bar *l* is provided with a tooth *t*, and with a notch *u* at the rear of the tooth; the segment-rack *r* is provided with an integral pawl *v* adapted 80 to be engaged or held by the tooth *t* by means of its horizontal extension *v'* and the notch *u*, and is provided also with a horizontal locking projection *w* adapted to be engaged in the hook *o*; and the back-plate *s* has at its upper 85 end an integral holding-pawl *x* adapted to engage the ratchet-teeth on the upper edge of the segment-rack, and a horizontal stop *y* at its lower end. A stop *z* (Fig. 4) extends horizontally from the end of the bar *l* behind 90 the rear edge of the segment-rack *r*.

In operation, when the loom is working the parts are as illustrated in Fig. 1, the bar *l* being down, the holding-pawl *v* slipping over the teeth on the ratchet-wheel *c* and preventing said wheel from rotating in the opposite direction, the part *v'* of the holding-pawl is in the notch *u* and held in position by the tooth *t*, the locking projection *w* is in engagement with the hook *o*, and the back-plate is 100 adjusted by means of a suitable nut on the bolt *p* so as to be rigid with the bar *l* and engage by means of the hold-back or stop *x* the desired tooth on the upper side of the segment-rack *r*. In the drawings the tooth engaged is the third tooth from the end, but the bar is adjusted to engage such tooth as is advisable according to the loom to which the let-back mechanism is attached. 105

When the filling breaks, the rock-shaft *h* is 110 rotated by the filling-stop-motion in the ordinary manner and lifts the let-back mechan-

ism by means of the usual arm *k*, lifting the bar *l* with its hook *o*, the segment rack, and the entire let-back mechanism into the position indicated by dotted lines in Fig. 2.

- 5 When the parts are thus lifted, the segment-rack *r* drops by gravity as far as the elongated slot *q* will allow out of engagement with the hold-back or stop *x*, and with its locking projection *w* and pawl *v* out of engagement 10 with the hook *o* and recess *u*. As the greater part of the weight of the rack is at the left of the pivot *p*, the rack swings toward the right until the pawl *v* rests against the stop *y*, all as shown in the dotted lines. The back- 15 plate *s* remains rigid with the arm *l*.

When the loom is ready to start, the parts are in the position indicated in full lines in Fig. 2, and when the loom is started the dropping of the let-back mechanism produced by the downward swing of the arm *k* from the position indicated in full lines in Fig. 2 to that illustrated in Fig. 1 allows time for the segment-rack *r* (which by means of the slot *q* extends considerably below the bar *l*) to let back the ratchet-wheel *c* the desired number of picks, until the hold-back *x* is lowered into engagement with the rack which has been rotated until the pawl *v v'* is again in engagement with the ratchet-wheel 20 and the tooth *t*, the stop *w* in engagement with the hook *o*, and the stop *z* (Fig. 4) bears against the plain or rear edge of the segment-rack, thus preventing a thin place in the cloth. 25

30 It will readily be seen that the substantially vertically slotted segment-rack in connection with the rotatively adjustable back-bar *r*, renders it possible to adjust the let-back mechanism to the desired number of teeth and picks, provides means for accurate timing of the rack as it descends in advance of the rest of the let-back mechanism, and renders the mechanism applicable to looms of different constructions. 35

40 Having thus fully described my invention, what I claim, and desire to secure by Letters Patent, is:—

45 1. In a let-back mechanism of the character and for the purpose described, a bar 50 adapted to be secured to and be operated by the arm extending from the rock-shaft of a loom, a hook on the end of the bar opposite that which is connected with said arm, a tooth extending downward from the lower 55 edge of the bar, a back-plate formed at its upper end with a horizontal hold-back or stop, a segment-rack between said bar and back-plate and formed with teeth on its up-

per edge adapted to be engaged by the hold-back and teeth on its lower edge, said segment-rack being provided with an elongated slot, a locking projection extending horizontally from the segment-rack into normal engagement with the said hook on the end of the bar, a bolt extending from the bar 60 through the slot in the segment-rack to the back-plate and holding said back-plate and bar adjustably in rigid connection, a pawl 65 extending from the lower edge of the segment-rack and adapted to be normally in engagement with a ratchet-wheel in the take-up mechanism, and a horizontal extension integral with said pawl extending into normal engagement with the tooth which extends downward from the lower edge of the 70 bar. 75

2. In a let-back mechanism of the character and for the purpose described, a bar adapted to be secured to and be operated by the arm extending from the rock-shaft of a 80 loom, a hook on the end of the bar opposite that which is connected with said arm, a tooth extending downward from the lower edge of the bar, a back-plate formed at its upper end with a horizontal hold-back or 85 stop, a segment-rack between said bar and back-plate and formed with teeth on its upper edge adapted to be engaged by the hold-back and teeth on its lower edge, said segment-rack being provided with an elongated 90 slot, a bolt extending from the bar through the slot in the segment-rack to the back-plate and holding said back-plate and bar adjustably in rigid connection, a stop 95 extending horizontally from the upper portion of the segment-rack and adapted to be engaged in said hook, a stop extending horizontally from the lower end of the back-plate and adapted to limit the rotation of the segment-rack, a stop extending from the rear 100 side of the hooked end of the bar behind the segment-rack, a pawl extending from the lower edge of the segment-rack and adapted to be normally in engagement with a ratchet-wheel in the take-up mechanism, and a horizontal extension integral with said pawl extending into normal engagement with the tooth which extends downward from the lower edge of the bar. 105

In testimony whereof I have signed my 110 name to this specification in the presence of two subscribing witnesses.

CHARLES LAVALLEE.
